CLAIM

The ornamental design for a speaker cabinet, as shown and described.

DESCRIPTION

FIG. 1 is a front perspective view of a speaker cabinet showing my new design;

FIG. 2 is a rear perspective view of the design of FIG. 1; FIG. 3 is a front elevation view of the design of FIG. 1; FIG. 4 is a rear elevation view of the design of FIG. 1; FIG. 5 is a left side elevation view of the design of FIG. 1; FIG. 6 is a right side elevation view of the design of FIG. 1; FIG. 7 is a top plan view of the design of FIG. 1; and, FIG. 8 is a bottom plan view of the design of FIG. 1.

The broken lines shown are included for the purpose of illustrating portions on the speaker cabinet that form no part of the claim.

The speaker grill pattern seen on the front interior surface in FIGS. 1 and 3 is understood to repeat throughout the surface upon which it is applied.
